SYSTEM AND PROCESS FOR THE REMOTE CONTROL OF SELECTORS OR SIMILAR UNITS

Fernand Pierre Gohorel, Antony, France, assignor to International Standard Electric Corporation, New York, N. Y., a corporation of Delaware

Application August 6, 1947, Serial No. 766,692
In France November 6, 1945

Section 1, Public Law 690, August 8, 1946
Patent expires November 6, 1965

10 Claims. (Cl. 177—353)

1

The systems are well known in which a selector may be directed, from a remotely located control device, to a given position (or group of positions).

To this end, the selector is equipped with a set of marking contacts which are scanned by a suitable scanning device, each position (or each group of positions) being characterized by a potential, the nature of a current or the phase angle of an alternating current applied to the corresponding marker contact. Means also are provided for the rotation of the selector to continue until such time as there exist a given relationship between the electrical condition of the marker contact and that of the control or directing device.

It is quite obvious that where the number of positions (or of groups of positions) is a large one, it becomes difficult to secure, for the marker contacts, such electrical conditions as lend themselves to simple identification. This had led to the use of electronic means, endowed with great sensitivity, but at the same time difficult of construction and critical of maintenance.

On the other hand, it is well known that, in a general sense, an electromagnetic relay of sufficient sensitivity to attract its armature with great rapidity does not release it with the same speed when its circuit is opened, this delay upon release becoming more substantial still when the current passing through the relay, instead of falling to a zero value, merely assumes a magnitude smaller than that of relay energization or operation.

Under such conditions, any relay which attracts its armature in the selector positioning unit, during the scanning of the marker contacts, while the scanning or hunting member passes on a position (or group of positions) at which the selector is not supposed to stop, will not immediately drop its armature as the scanning member leaves the position (or group of positions) just alluded to. Furthermore, if the speed of said device be of sufficient value, which is practically the case of selectors, such a relay thus may cause false positioning during the scanning of the following marker contacts.

One of the characteristics of the invention will be found in the fact that the marking potentials are so arranged that, bearing in mind the scanning order of the corresponding marker contacts, it is not necessary to energize any relays upon passing the position (or group of positions) which precedes the one at which the selector must be stopped.

A process for the adjustment of a selector having n positions (or n groups of positions) in ac-

2

cording with the above mentioned characteristic is obtained by the following combination in which:

- 5 1. Use is made on $n-1$ sources of direct current at the same potential u , series connected, which gives n potential levels or steps.
2. If the n marker contacts of n positions be designated by 1, 2, 3, 4 . . . n , counting in the order of their scanning, they are connected to the 10 potential steps according to the following rule: contact 1 to 0 potential, contact 2 to

$$\frac{n+1}{2} \cdot u$$

- 15 potential, contact 3 to u potential, contact 4 to

$$\frac{n+3}{2} \cdot u$$

- 20 potential, contact 5 to $2u$ potential, contact 6 to

$$\frac{n+5}{2} \cdot u$$

- 25 potential, etc. . . . If n be an even number, the values

$$\frac{n+1}{2} \cdot u, \frac{n+3}{2} \cdot u$$

- 30 are rounded off to the nearest integer below the actual figure obtained.

- 35 3. A provision is made, in the directing or orienting device, inserting them in the directing or control circuit, for two series or parallel connected relays, the first of one is capable of attracting its armature at a potential difference equal to y while the second, or marginal one, is capable of attracting its own armature only for a potential difference of $2u$. Said relays are connected, on the one hand, with the scanning device 40 of the selector marker contacts and, on the other hand, with a potential lever 1 or step which depends on the position at which the selector is to be stopped, provisions being made for them to be energized only by a current circulating in a given 45 direction.

- 50 4. Scanning of the selector is caused throughout the time during which, either the first relay is not attracted, or both simultaneously attract their respective armatures.

- 55 Another process which is an application of the characteristic indicated above and which makes it possible to reduce the number of the wires between the selector and the controlling or positioning device is constituted by the following combination, in which:

1. Use is made, for the marking of n groups of positions, of n sources of direct current,

$$\frac{n}{2}$$

of which have their negative terminals connected to a common point, while the remaining

$$\frac{n}{2}$$

have their positive terminals connected to said common point. The voltages of the

$$\frac{n}{2}$$

"positive" sources are all different from one another but may be respectively equal to the voltages of the

$$\frac{n}{2}$$

"negative" sources. One thus provides

$$\frac{n}{2}$$

steps of "positive" potentials and

$$\frac{n}{2}$$

steps of "negative" potentials.

2. The

$$\frac{n}{2}$$

groups of marker contacts of the selectors of odd order are connected to the positive (or negative) potential steps, while the even order remaining

$$\frac{n}{2}$$

groups are connected to the negative (or positive) potential steps or levels. Where n is odd, two consecutive groups of marker contact groups are connected to two positive (or negative) steps, in such a manner that the step having the lower voltage precedes, in the direction of scanning, the one having the higher voltage.

3. A provision is made, in the controlling or directing device, for several relays connected either in series or in parallel and capable of operating only with a given direction of current, the armature attraction or non-attraction of said relays being dependent on the potential difference applied to their terminals. These relays are connected, on the one hand, to the scanning device of the selector and, on the other hand, to the common point of all the current sources and the current direction for which they are attracted, as well as their attraction or non-attraction combinations, depend on the group of lines or on the line to which the selector is to be directed.

4. Scanning of the selector and its positioning are controlled according to the attraction or non-attraction combination of the relays of the positioning or direction device.

In the process outlined above, the common point of the current sources, as well as one of the terminals of the relay group may be grounded, which does away with the need for a connecting wire between the selector and the directing device. This arrangement is of particular advantage when the selector and the directing device are not installed in a single room (such as is the case, for instance, in telephone networks having several central offices).

Another process, according to the characteristic of the invention, which makes it possible substantially to reduce the number of the potential steps, and thus the precision needed in the operation of the control relays consists, in combination with the processes discussed above, of the following:

1. An alternating current source or several alternating current sources having different voltages or frequencies are connected in series with the direct current sources, between the latter and some of the marker contacts of the selectors. If there be available, for instance, n direct current marking potentials, the superimposition of a single alternating current on each direct current source will provide $2n$ marker steps, while, with two sources of alternating current, the number of marker steps would be raised to $3n$.

2. The marker contacts of the selectors, in their order of scanning, are alternately connected to a direct current potential step and to a potential step obtained by means of the superimposition of the alternating current source on the direct current source used for the preceding marker contact. The order of the direct potential steps is chosen in the manner which has been outlined above with relation to another process. In cases where several alternating current sources are available, the various potential steps obtained by the superimposition, to a direct current, of each one of the alternating current sources, are connected in succession to a series of the selector marker contacts before another direct current potential level is connected to the next contact in line.

3. Scanning of the selector and its position are controlled by the action of relays which are responsive, not only to direct current, but also to alternating current.

4. In combination with the above outlined processes, it is possible further to increase the number of the positions which can be assumed by the selectors, when they are equipped with a drive mechanism of the "step by step" type, and when the selector can take only one position for each call number registered by the controlling or directing device. Such, for instance, is the case of the line selectors or final selectors used in automatic switching telephony.

According to the invention, the selector is divided into groups, each of which comprises a certain number of positions, the first of which in turn is marked by a potential level or step, and to which the selector may be directed or positioned by the controlling or directing device in accordance with one of the processes which have already been described above. When this preliminary positioning or directing has been completed, the controlling or directing device sends out as many impulses as are needed to cause the selector to move ahead to the final position to which it is to be directed. The controlling or directing device of the selector is placed in series, for the preliminary direction, with a rectifier which passes only one current alternation and a source of alternating current while, for the final positioning or directing, it is connected to an impulsive contact and a source of direct current.

Various embodiments of the processes outlined, in accordance with the principles of the invention, will now be described as non-restrictive examples, in relation with the appended figures. These figures show only such circuit elements as are necessary for an understanding of the invention.

In the directing process of Figure 1, two relays A and B are provided in directing device O. These relays are inserted in a circuit which is connected, on the one hand, to the scanning device of selector S, namely wiper F and, on the other hand, to unilaterally conducting elements Q1 and Q2. According to the number received by the controlling or directing element, one of contacts sa1 to sa5 is closed. Relay A can attract its armature when there is a potential difference equal to u and relay B can attract its own armature only when such potential difference as is present is equal to $2u$.

Marker contacts 1 to 5 of selector S are connected as shown on the figure.

It will now be assumed that contact sa3 is closed, namely that selector S must be directed to position 3. When director O and selector S have been connected, the circuit of drive electro-magnet R is closed through rest contact a1 of relay A. When wiper F reaches the third position, the following circuit is completed: negative polarity on U3 at contact 3 of S, wiper F, relays A and B in series, unilaterally conducting element Q1, closed contact sa3 and positive polarity on battery U3. Relay A attracts its armature and relay B remains at rest. Through its rest contact a1, relay A opens the circuit of drive electro-magnet R and selector S stops at the third position.

Through its work contact a1, relay A completes, by way of rest contact b1 of B, the circuit of relay C, which causes, in the directing or controlling unit, the operations which follow the stopping of the selector.

The case will now be taken up of the possibility of false positioning when wiper F passes on bank contacts 1 and 2.

When wiper F passes on bank contact 1, the following circuit is completed: negative terminal of battery U4, contact 1 and wiper F, series connected relays A and B, element Q1, contact sa3, positive terminal of battery U3. Since the two batteries, U3 and U4 are connected in series in the circuit relays A and B will attract their respective armatures. Through its work contact b2, relay B completes the circuit of R, which is open at a1. Selector S thus will continue the scanning motion. Through its contact b, relay B makes a break in the circuit of C and this last mentioned relay can not be energized.

When wiper F passes on position 2, the positive polarity of U2 is placed on said wiper. The circuit of relays A and B cannot be completed due to the fact that element Q2 is not placed in the circuit. Relays A and B drop their respective armatures and S continues the scanning.

It will be observed that relay B, which had been energized at position 1, drops its armature at position 2 or, in other words, there is no need for any energized relay at the position which precedes the one to which the selector must be directed. By having reference to the directing or controlling circuits, it will readily be seen that stopping is effected by the energizing of relay A, at position 1, through Q1 (U4); at position 2, through Q2 (U2); at position 4, through Q2 (U1), and at position 5 through Q1 (U2). Furthermore, there can be no false positioning.

Figure 2 shows a variation on the process of Figure 1, which makes it possible to reduce the number of the wires needed between the directing or controlling unit and the selector.

A certain number of batteries U3, U2, U1, U'1, U'2, etc. . . . are arranged in selector S, having

the same voltage u and connected in series, the common point between batteries U1 and U'1 being grounded. This constitutes a certain number of potential steps or levels, namely 6 in the example under review, which are respectively equal to $-3u$, $-2u$, $-u$, 0, $+u$ and $+2u$. The negative potential steps or levels are connected respectively to the bank contacts associated with wiper F of selector S on odd positions 1, 3 and 5, while the positive potential steps or levels are respectively connected to positions 2 and 4.

It will now be assumed that contacts sa3, sb3 are closed, namely that the selector has to be directed to position 3.

As soon as directing device O is connected with the selector S to be directed, the following circuit is completed: battery, electro-magnet R, contact sb3, rest contact a1 associated with relay A, ground.

Electro-magnet R then causes, according to a well known process, the progression of its wipers in automatic rotation. When said wipers reach position 3, the following circuit is completed: negative terminal of battery U2, bank contact 25 and wiper F at position 3, unilaterally conducting element Q2, contact sa3, left hand windings of relays A and B in series, ground and, in selector S, ground and the positive terminal of battery U1.

Relay A has been so designed that it attracts its armature only in the presence of a voltage equal to $2u$ at least, if it is energized on its left hand winding and to u if it is energized on both of its windings. Similarly, relay B has been so 35 designed that it is energized by a voltage equal to $3u$ at least, if working on its left hand winding and $2u$ if working on both windings.

Relay A thus will be the only one to attract its armature, since the above outlined circuit 40 closes through two batteries, each of which has an E. M. F. equal to u ; it opens, at a1, the drive circuit of the selector and completes, by way of its work contact a2, the following circuit: battery, relay C, contact sb3, work contact a2, rest 45 contact b2 associated with relay B, ground. Relay C is energized and causes, within the directing or controlling unit, the various operations which follow, the stopping of the selector.

Even as was the case with the arrangement 50 of Figure 1, let us now review the possibility of false positioning when wiper F passes on positions other than position 3. When it passes position 1, the following circuit is completed: negative terminal of battery U3, bank contact and 55 wiper F at position 1, unilaterally conducting element Q2, contact sa3, left-hand winding of relays A and B, ground and, in selector S, ground and positive terminal of battery U1. Relays A and B are both energized, due to the presence 60 of a potential difference $3u$; at a1, relay A makes a break in the drive circuit of the selector but, by way of its work contact b1, relay B restores continuity to said circuit and the selector continues its progression. Relay C being of the delayed attraction type, remains at rest, even if its circuit has temporarily been completed at b2 and a2, due to the non-simultaneity of the operation of relays A and B. When the selector passes 65 position 5, relays A and B, the circuits of which are completed only through battery U1, remain at rest and the progression of said selector continues. When the selector passes even positions 2 and 4, batteries U'1 and U'2 are the ones to

intervene, but the circuit of relays A and B can

not be completed due to the presence of unilaterally conducting element Q2.

It will be observed that relay B, energized at position 1, has all the needed time to drop its armature at position 2, thus does not present the risk of being held at position 3, which would make it impossible for the selector to stop.

A study of the various directing or controlling circuits will show that stopping is caused by the energizing of relay A, at position 2, through battery U'1, rectifier Q1 and the two series connected windings of A, at position 4, through U'1, U'2 and Q1, at position 5, through U1 and Q2. False positioning is made impossible due to the fact that, on the even numbered positions, the circuit of relays A and B can be completed only if the directing or controlling unit is on an odd numbered position due to the presence of one of the two unilaterally conducting elements Q1 and Q2 and conversely. On the other hand, when rectifiers Q1 and Q2 do not oppose the passage of current, the voltage is either too weak, which makes it impossible for relay A to be energized, or too high, which causes relay B to be energized and the progression of the selector to continue.

When the selector has to be directed to position 1, contacts sa1, sb1, sc1 are closed, the drive circuit passes through: battery, electro-magnet R, contact sc1, rest contact b1, ground, stopping being effected by relay B, which is energized through batteries U1, U2, U3, rectifier Q2 and contact sa1. The circuit of relay C then is completed through b2 and sb1. False positioning or directing is impossible for the very reasons which have been discussed in the above paragraph.

Figure 3 shows a device which makes it possible to direct a selector to $2n$ positions by making use of only n batteries,

$$\frac{n}{2}$$

of which (U1, U2, U3) have their positive terminal connected to a common point which is grounded in the example illustrated, and the other

$$\frac{n}{2}$$

of which (U'1, U'2, U'3) have their negative terminal connected to said common point. The voltages of batteries U1, U2, U3 are different from one another but may respectively be equal to those of batteries U'1, U'2, U'3. In order to make matters clearer, let $u1, u2, u3, u'1, u'2, u'3$ be the respective voltages of batteries U1, U2, U3, U'1, U'2, U'3 with:

$$\begin{array}{ll} u3 < u2 < u1 & u1 = u'1 \\ u'3 < u'2 < u'1 & u2 = u'2 \\ u3 = u'3 & \end{array}$$

The negative terminals of batteries U1, U2, U3 are respectively connected to positions 1, 5 and 9 of selector S while the positive terminals of U'1, U'2, U'3 are connected to positions 3, 7 and 11. Each even numbered position is connected to the odd position which immediately precedes it through an alternating current generator which may, by way of example, be one of the windings of the secondary of a transformer T. Relay A has been so designed as to attract its armature with a voltage equal at least to $u2$, if its left-hand winding is the only one in the circuit, and with a voltage equal to $u3$ at least, if both windings are functioning. Relay B has been designed to attract its armature for a voltage equal to $u1$ at

least if its left-hand winding is the only one in the circuit and for a voltage equal at least to $u2$ if both windings are in the circuit.

Let it be assumed that the selector must be directed to position 5; contacts sa5, sb5, sc5, sd5, se5, of the directing or controlling element O then are closed. As soon as said controlling unit is connected to selector S, which is to be directed or positioned, the following circuit is completed: battery, drive electro-magnet R, contact sc5, rest contact a1 associated with relay A, ground. The drive electro-magnet R causes the selector wipers to move ahead in automatic rotation. When said wipers reach position 5, the following circuit is completed: negative terminal of battery U2, bank contact and wiper F of the selector at position 5, unilaterally conducting element Q1, contact sa5, left-hand windings of relays A and B, connected in series, ground; and, in selector S, ground and positive terminal of battery U2. The voltages needed to energize relays A and B on the left-hand winding are, respectively, $u2$ and $u1$, so that relay A is the only one to attract its armature, closing at a2 the following circuit of relay C: battery, relay C, rest contact d2, associated with relay D, contact sb5, work contact a2, rest contact b2 associated with relay B, ground. Relay C is energized causing, in the directing or controlling unit, the various operations which follow the stopping of the selector.

It is impossible for said selector to stop on any position but the fifth. If we take position 1, we see that battery U1 is the one to intervene so that relay B is energized at the same time as relay A and causes, through its work contact b1, the re-starting of the selector. At position 9, battery U3 is placed in the circuit and relay A itself is unable to become energized with the flux generated by its left-hand winding only. At positions 3, 7 and 11, batteries U'1, U'2 and U'3 are the ones placed in the circuit; relays A and B can not be energized due to the presence of unilaterally conducting element Q1. At positions 2, 4, 8, 10, 12, false positioning is ruled out for motives identical to those which oppose stopping at the odd numbered position which immediately precedes them. The alternating currents generated by windings t1 to t6 will be so chosen as not to cause unwanted operation of relays A and B. At position 6 which immediately follows position 5, or the stopping position, the following circuit is completed: negative terminal of battery U2, winding t3, bank contact and wiper F at position 6, unilaterally conducting element Q1, contact sa5, left-hand winding of relays A and B, ground and, in selector S, ground and positive terminal of battery U2, winding t3, bank contact and wiper F at position 6, work contact a3, contact se5, capacitor C, bridge rectifier such as made up of elements Q3 to Q6, ground. Relay D is energized due to the effect of the rectified current and completes, by way of its work contacts d1 and sd5, the drive circuit of the selector, which otherwise would be open at a1; by the opening of its rest contact d2, it opposes the unwanted energizing of relay C. It will be noted that, according to the invention, none of relays A, B and D has its circuit completed at position 4 of the selector, which immediately precedes stopping position 5.

It will now be assumed that the selector has to be directed to an even numbered position, position 6 for instance. Contacts sa6, sb6, sc6, sd6, se6, are closed. When the selector moves on to position 6, the following circuit is completed: negative terminal of battery U2, winding t3, bank

contact and wiper F of the selector at position 6, unilaterally conducting element Q1, contact sb6, left-hand winding of relays A and B, connected in series, ground; and, in selector S, ground, positive terminal of battery U2 with, in parallel across the circuit outlined above, contact se6, capacitor C, relay D through bridge rectifiers Q3 to Q6, ground. Relay A is the only one to be energized, to the exclusion of relay B, for reasons explained elsewhere; the alternating current, on its side, 10 causes the operation of relay D, after its rectification by bridge rectifier Q3, Q4, Q5, Q6. The drive circuit of the selector is open at a1 and d1. Relay C is energized by way of: battery, relay C, work contact d2, contact sb6, work contact a2, rest contact b2 and ground.

No false positioning is possible; at positions 1 and 9, the voltage is such that relays A and B both attract their armatures or both remain at rest. On positions 3, 7 and 11, rectifier Q1 makes it impossible for relay A to be energized; at positions 2, 4, 8, 10, 12, the reasons which make it impossible for the selector to stop are the same as those which rule out stopping at the odd-numbered positions which immediately preceded them; at position 5, which immediately precedes the stopping position, the drive circuit of the selector is completed through rest contact d1, associated with relay D and sb6.

Study of the various directing circuits will show that stopping of the selector is effected at position 1, by the energizing of relay B through its left-hand winding, through battery U1 and rectifier Q1, at position 3, by the energizing of relay B on its left-hand winding through U'1 and Q2, at position 5, by the energizing of relay A on the left-hand winding through U2 and Q1, at position 7 by the energizing relay A on its left-hand winding through U'2 and Q2, at position 9, by the energizing of relay A on both of its windings through U3 and Q1, on position 11, by the energizing of A on its two windings through U'3 and Q2. At any even-numbered position, stopping is effected as at the odd numbered position which immediately precedes it with, in addition, the energizing of relay D.

It will also be noted, generally speaking, that the selector can not stop at a position different from the one required; either the direction of flow of the current is such that neither relay A 50 nor relay B can be energized and rotation is continued through rest contacts a1 and b1, or else the battery tension applied to the circuit is too high, which causes relay B to be energized and the rotation of the selector to continue by way of work contact b1; or else the voltage of the battery placed on the circuit is too low, neither of relays A and B being able to attract their respective armatures and rotation being continued by way of a1 or b1, or again the position on which the selector is even, rather than odd numbered, which causes relay D to be energized through one of contacts a3 or b3 and the rotation of the selector still to continue through work contact d1; or, finally the position passed by the selector is odd, rather than even numbered, in which case relay D remains at rest and causes rotation to be continued by way of its rest contact d1.

It will also be seen that, according to the invention, no relay which might cause unwanted rotation has its circuit completed at the position which immediately precedes the stopping position, neither relay A nor relay B, due to the presence of unilaterally conducting elements Q1 and Q2, nor either relay D, due to contacts a3 and b3.

It has been assumed, in the above discussion, that the voltages of batteries U1, U2, U3 were respectively equal to those of batteries U'1, U'2, U'3. It is obvious that this condition is not by any means indispensable and that the voltage of battery U'1, for instance, may be smaller than that of battery U1, provided there be a sufficient margin between said voltage and the one immediately smaller, namely u2 or u'2.

Figure 4 shows a directing or controlling device which embodies a combination of the processes described above and the process whereby directing is effected through the sending out of impulses.

The selector illustrated comprises a certain number of positions which are grouped in tens; for the clarity of the illustrations, only tens numbers 1, 2 and 3 have been shown, as well as only the four first positions of each ten. The first positions of each ten, say 10, 20 and 30, are connected to batteries U3, U2, U1, U'1, U'2, which are arranged similarly to the manner in which they are shown in Fig. 2, although any one of the above described processes might be used, while the bank contacts associated with wiper F at the other positions are insulated. The control unit O may be similar to that shown in Fig. 2 except that the electro-magnet R is not self-interrupting and is connected to ground, that the armatures associated with contacts a1 and b1 are connected together and through a unilaterally conducting element Q7 and generator Ge2 to ground, and that the lead connected to the electro-magnet R is also connected to the work contact ii of a relay I, the associated armature being connected through a battery Ui to ground.

It will be assumed, by way of example, that one has to direct selector S to position 23. When said selector is connected to director or control unit O, the following circuit is completed: ground, drive electro-magnet R of selector S, contacts sc2, rest contact a1, associated with relay A, unilaterally conducting element Q7, generator Ge2, ground. When the selector reaches the first position of the required ten, position 20, in the example under review, contact a1 opens in a similar manner to that described in connection with Fig. 2, contact b1 is not energized, and the selector stops. Thereupon the relay I is operated and released three times, in the example given, by means not shown, so as to cause contact ii to close three times in succession, and three direct current impulses, supplied by battery Ui, are sent to electro-magnet R, causing it to move ahead to position 23.

It is quite obvious that the devices described above have been given only by way of example and that it would be possible, without thereby exceeding the scope of the invention, to increase the number of the positions to which the selector can be directed, by the device of providing a greater number of batteries, and a whole range of alternating currents differing from one another by their amplitude, their frequency or their phase angle.

I claim:

1. In a selector system, a selector switch comprising a test wiper, a plurality of test terminals, and electric driving means for said switch, a plurality of potential sources connected to said test terminals, a first test relay having contacts in the circuit of said switch driving means and adapted to operate at a predetermined voltage, a second test relay having contacts in the circuit of said switch driving means and adapted to

operate at a predetermined different voltage, the said relay contacts being arranged so that the operation of one of said relays without the other will de-energise the switch driving means, while the operation of both relays will not break the circuit of said switch driving means, and marking means including a pair of contacts for each test terminal of said switch and unidirectional current devices for marking a position of the switch for selection, the windings of said relays and said marking means being serially connected between said test wiper and said potential sources, the connection between said marking means and said sources being over a lesser number of leads than there are test terminals.

2. In a selector system, the combination according to claim 1, in which there are two unidirectional devices, one connected in series with certain of said marking contacts and the other connected in a reverse direction in series with certain other of said marking contacts.

3. In a selector system, a combination according to claim 2 in which the sources of potential are connected together in series.

4. In a selector system, the combination according to claim 3, in which the marking means is connected by at least one lead to a junction point between two of said sources.

5. In a selector system, the combination according to claim 1, in which there are two unidirectional devices, one connected in series with certain of said marking contacts and the other connected in a reverse direction in series with certain other of said marking contacts, and in which said sources of potential are connected together in series and certain of said marking contacts are connected to the junction point between two of said sources while certain other of said marking contacts are connected to the junction points between others of said potential sources.

6. In a selector system, the combination according to claim 1, in which two unidirectional devices are provided one connected in series with certain of said marking contacts and the other connected in the reverse direction in series with certain other of said marking contacts, said potential sources being connected together in series, and in which said test relays are each provided with two windings, certain of said marking contacts being arranged to connect one winding of each relay in series while certain other of said marking contacts being arranged to connect all of said windings in series, there being a single wire connecting said marking contacts with a junction point between two of said potential sources and in which additional marking contacts are provided for reversing the operation of said relays with respect to said switch driving means.

7. In a selector system, the combination according to claim 1 in which the potential sources are all connected to a common point, and in which two unidirectional devices are provided, one connected in series with certain of said mark-

ing contacts and the other connected in the opposite direction with certain other of said marking contacts, and in which the test relays are each provided with two windings, the connections being such that certain of said marking contacts connect one winding of each relay in series while certain other of said marking contacts connect all of said windings in series, there being a single connection between said common point and said marking contacts, and in which additional marking contacts are provided to reverse the operation of said test relays with respect to said switch driving means, and in which is provided a plurality of potential sources having different characteristics from said first-mentioned potential sources, certain of said test terminals being connected to one of said first potential sources and one of said second potential sources in series, a third test relay connected between said test wiper and the common point on said first potential sources, said relay being under control of said first and second test relays, means for making said third test relay responsive only to one of said second sources of potential, and means controlled by said third test relay for additionally controlling the energization of said switch driving means.

8. In a selector system, the combination according to claim 1 in which the sources of potential are direct current sources, and in which a second plurality of alternating current sources are provided connected to alternate ones of said test terminals in series with the direct current potentials connected thereto, and in which additional controlling means is provided responsive only to said alternating current sources for further controlling the switch driving means whereby the number of test terminals may be increased.

9. In a selector system, the combination according to claim 1 in which a third relay is provided under the control of the first and second test relays for performing an operation when the selector switch comes to rest at the desired position.

10. In a selector system, the combination according to claim 1, in which the connections between the sources of potential and the test terminals and the connections between the relays and the marking contacts are such that neither of said relays is operated when the wiper of the selector switch is on a test contact immediately preceding the marked position.

FERNAND PIERRE GOHOREL.
